ROGER K. LEE, OF HIGHLAND PARK, MICHIGAN, ASSIGNOR TO CHRYSLER CORPORATION, OF DETROIT, MICHIGAN, A CORPORATION OF DELAWARE

RADIATOR CAP

Application filed May 21, 1930. Serial No. 454,450.

This invention relates to an improved cap for spouts, particularly for filling spouts of the type used in motor vehicle radiators. Heretofore, in radiator caps of the type which have ornamentations such as wings and other decorating means indicative of speed, it has been difficult to secure the cap on a radiator spout so as to form a liquid tight seal and at the same time position the cap so that the ornamentation is properly located. When threaded connections are used between the radiator cap and filling spout, frequently the threads are not formed so as to position the ornamentation in a proper direction with respect to the length of the car when the cap is tight.

The main objects of this invention are to provide a yieldable, expandable member in a cap of this kind which forms a water tight seal with the walls of a radiator spout; to provide means for releasably expanding the yieldable member after it is seated in a spout; to provide means of this kind which is operable by manipulation of a decorative member with which the cap is provided; and to provide a radiator cap of improved construction which may be conveniently mounted so as to place the decorative member in a predetermined angular position when the cap is held against displacement by expansion of the yieldable element.

An illustrative embodiment of this invention is shown in the accompanying drawing, in which:

Fig. 1 is a central vertical section showing a cap embodying my invention mounted on a radiator filling spout.

Fig. 2 is a horizontal section taken on line 2-2 to Fig. 1.

Fig. 3 is a central vertical section showing a further development of my invention.

In the form shown, the radiator cap has a cylindrical neck portion which includes a cup shaped yieldable member 1 having a substantially planar end and cylindrical side

walls 2. Formed on the outer edge of the side walls 2 is an inwardly extending peripheral flange 3. The yieldable member 1 is located between an outer substantially rigid disc shaped plate 4 which has lugs 5 on its periphery and an inner substantially rigid cup shaped member 6 having a peripheral flange 7 at its open end which engages the open end edges and flange 3 of the yieldable member 1. The inner portion of the rigid part 6 extends into the interior of the yieldable member 1 and is provided with a central aperture 8 which registers with corresponding apertures 9 and 10 in the member 1 and plate 4.

The neck of the cap is seated in the open end of a radiator filling spout 11 which is substantially cylindrical in shape and is enclosed by a radiator shell 12. Formed in the outer edge of the spout 11 are slots 13 in which the lugs 5 and plate 4 are seated for securing the plate against rotation relative to the spout. A bolt 14 having a head 15 on its inner end engaging the cup shaped rigid member 6 extends outwardly through the registering apertures 8, 9 and 10 and is held against displacement from the neck of the cap by a cotter pin 16. The shank 14' of the bolt 14 is square and the apertures 8, 9 and 10 are of corresponding shape thus preventing rotation of the bolt relative to the neck part of the cap.

Threaded on the outer end of the bolt 14 is a nut part 17 having an ornamentation 18 thereon. The nut part 17 is provided with an end skirt 19 forming a recess 20 into which the open end of the spout 11 extends. Formed on the end wall 21 of the recess 20 is an annular ridge 22 which bears against the outer surface of the disc 4 when the nut member 17 is screwed downwardly.

In operation, the neck of the cap is inserted into the open end of the spout 11 when the nut part 17 is released. When the neck is in place the nut part 17 is tightened on the bolt

14 thereby causing the yieldable member 1 to be compressed and forcefully urging the side walls thereof against the inner periphery of the spout 11. This action forms a water tight seal and firmly holds the cap in place.

15 The nut part 17 may be slacked off or tightened further as required to bring the ornamentation 18 into a proper angular relation with respect to the length of the vehicle 10 upon which it is mounted. If it is found that this adjustment relaxes or augments the compression of the yieldable member 1 excessively, the nut part 17 may be loosened so as to permit angular adjustment of the neck part of the cap relative to the spout 11.

16 During compression of the yieldable member 1 the side walls 2 thereof are restrained from outward expansion by the spout 11 but they are free to bulge inwardly into the annular recess 23 between the sides of the rigid cup shaped member 6 and the inner periphery of the side wall 2 of the yieldable member which is provided by the flange 3 thereon. This freedom of the rubber member to bulge 25 inwardly allows the ornamented nut part 17 to be freely adjusted within substantially wide limits without relaxing the pressure exerted on the side walls of the radiator spout and without the application of excessive force.

17 In the form shown in Fig. 3, the radiator filling spout 11 in connection with which my improved radiator cap is illustrated has an outwardly bulged part 23 forming an annular groove or depression 24 in the inner periphery of the spout. The cap is of the construction described above and when the rubber member 2 thereof is compressed, the sides thereof are expanded into the groove 24, thereby securely holding the cap against unintentional displacement from the spout.

18 Although several specific embodiments of this invention have herein been shown and described, it will be understood that various changes including the size, shape and arrangement of parts may be made without departing from the spirit of my invention and it is not my intention to limit its scope other than by the terms of the appended claims.

I claim:

19 1. In a spout cap, a stem having inner and outer rigid members, and an intermediate yieldable member, a lug on one of said rigid members for securing said stem against rotation, and means on said cap for compressing said intermediate member between said rigid members and against the inner periphery of a spout.

20 2. In a spout cap, a stem including inner and outer rigid members and an intermediate rubber member therebetween, lugs on one of said rigid members adapted to seat in a recess in the wall of a spout, and means on said cap for compressing said rubber member against the inner periphery of a spout.

21 3. In combination, a radiator filling spout

22 having notches in its outer extremity, an outer support located in the upper end of said spout having projections seated in said notches, an inner support located in spaced relation to said outer support, a rubber member between said supports and engaging the inner periphery of said spout, and means co-acting with said supports comprising a threaded stem and nut member for compressing said rubber member firmly against the inner periphery of said spout, and an ornament on said nut member adapted to be positioned by rotation thereof during compressing of said rubber member.

23 4. In combination, a radiator filling spout, a spout cap including a pair of spaced rigid elements and an intermediate yieldable element, a member connecting said elements for compressing said intermediate element against the sides of said spout and securing said elements against relative rotation, and means on one of said rigid elements for co-acting with said spout to secure said elements against rotation relative thereto.

24 5. In combination, a radiator filling spout, a spout cap including a support, a vertically shiftable member mounted on said support, a clamping member on the inner end of said shiftable member comprising tubular part having side walls spaced from the sides of said spout, means for urging said support and clamping member together, and a yieldable member having a tubular portion between said support and clamping member, the inner periphery of the tubular portion of said yieldable member being spaced from the outer periphery of the tubular portion of said clamping member so as to permit inwardly bulging of the sides of the tubular portion of said yieldable member when the outer periphery of the latter is compressed against the side walls of said spout.

25 6. In combination, a radiator filling spout, a spout cap including a support, a vertically shiftable member mounted on said support having a threaded outer end, a clamping member mounted on the inner end of said shiftable member having a tubular portion spaced from the sides of said spout and a protruding flange, a yieldable sleeve located between said support and clamping member and seated on said flange, there being clearance between the adjacent sides of said clamping member and yieldable sleeve, and a nut threaded on said shiftable member having an ornamentation thereon for compressing said yieldable sleeve between said support and flange, said clearance allowing inward bulging of said sleeve after the outer side thereof is compressed against the side of said spout for permitting the ornamentation to be adjustably positioned by further rotation of said nut part.

26 7. In combination, a radiator filling spout having a groove in its inner periphery and

notches in its outer extremity, a support having lugs engaged in said notches and a central aperture, a threaded member slidably mounted in said aperture and secured against 5 rotation relative to said support, a rigid member on said threaded member, an expansible element between said support and said rigid member, and a cap thread on said threaded member for clamping said expansible element 10 between said support and rigid member so as to expand the same into said groove.
